SMOKERS' LIGHTERS

Fred Perlin, Oconomowoc, Wis., assignor to The Parker Pen Company, Janesville, Wis., a corporation of Wisconsin

Application June 22, 1953, Serial No. 363,265

11 Claims. (Cl. 67—7.1)

This invention relates to lighters of the type commonly employed in lighting cigars and cigarettes and has to do particularly with a lighter of the so-called gaseous fuel type which employs as a fuel a normally gaseous material which is stored in the lighter in the form of a compressed or liquefied gas and is discharged and burned in gaseous form.

An object of the present invention is to provide an improved lighter of the gaseous fuel type having an improved mechanism for controlling the discharge of fuel.

Another object is to provide a lighter of the gaseous fuel type having an improved mechanism for controlling the discharge of fuel and simultaneously igniting the discharged fuel.

A further object is to provide a lighter of the gaseous fuel type having improved means for adjusting the rate of flow of gas from the tank or container of the lighter.

Another object is to provide a lighter of the gaseous fuel type wherein the rate of flow of gas from the tank is controlled in such manner as to be generally uniform regardless of the temperature of the air surrounding the lighter, whereby the flame is maintained at a generally uniform height.

Another object is to provide a lighter of the gaseous fuel type having a simple, positive and effective mechanism for controlling the flow of gas from the tank and for igniting the discharged gas.

A further object is to provide a lighter of the gaseous fuel type having a sparking wheel, which includes improved means for actuating the sparking wheel, and an improved valve construction for controlling flow of fuel from the tank to a lighting station, together with means for controlling the operation of the valve by the operation of the means for actuating the sparking means so that fuel is emitted at the lighting station immediately prior to actuation of the sparking wheel.

Other objects and advantages of the invention will appear from the following description taken in connection with the appended drawings, wherein:

Figure 1 is a top plan view of a lighter made according to the present invention, with portions broken away and shown in section;

Fig. 2 is a fragmentary sectional view taken on line 2—2 of Fig. 1, with the bottom portion of the tank of the lighter omitted;

Fig. 3 is a fragmentary sectional view taken on line 3—3 of Fig. 1 showing particularly the valve and flow control structure;

Fig. 4 is a view taken substantially on line 4—4 of Fig. 3;

Fig. 5 is a sectional view taken on line 5—5 of Fig. 3;

Fig. 6 is an exploded perspective view of certain elements of the structure of Fig. 3;

Fig. 7 is a fragmentary sectional view taken on line 7—7 of Fig. 1;

Fig. 8 is a fragmentary sectional view taken on line 8—8 of Fig. 1;

2

Fig. 9 is a fragmentary sectional view taken on line 9—9 of Fig. 1;

Fig. 10 is a fragmentary view taken from the right of Fig. 9 but with a portion broken away;

5 Fig. 11 is a sectional view taken on line 11—11 of Fig. 2;

Fig. 12 is a sectional view taken on line 12—12 of Fig. 2, and showing certain elements in different positions relative to Fig. 11;

10 Fig. 13 is a view similar to Fig. 12 but with certain elements in different positions relative to Fig. 12;

Fig. 14 is a bottom view of the sparking wheel, taken substantially on line 14—14 of Fig. 2;

15 Fig. 15 is a view taken substantially on line 15—15 of Fig. 2;

Fig. 16 is an axial sectional view of a modified form of valve suitable for use in the lighter instead of the valve of Fig. 3; and

Fig. 17 is a fragmentary sectional view of the metering 20 plug included in the valve of Fig. 16.

Referring particularly to Figs. 1 and 2, the lighter, made according to the present invention, includes a chassis 20 and a tank 22 together with an enclosing casing 24. The casing 24 is herein shown diagrammatically and may assume any desired and suitable form such,

25 for example, as a casing generally similar to the casing of my copending application Serial No. 333,415 filed January 27, 1953. The chassis 20 and tank 22 are normally contained in the casing in the ordinary use and 30 operation of the lighter, but the casing may of course be so constructed as to enable the chassis and tank to be removed from and inserted in the casing when desired, as for example when it is desired to replace an empty tank with a charged tank.

35 As will be apparent as the detail description proceeds, the chassis 20 includes essentially all of the operating parts of the lighter while the tank 22 contains the supply of fuel which is conducted through the valve means in the chassis to the burner as controlled by the means for 40 actuating the flint sparking wheel in the normal use of the lighter.

The lighter is preferably made of a suitable metal throughout its construction except certain elements as will be referred to specifically such, for example, as the flint, 45 resilient sealing means and resilient metering means.

The chassis 20 includes a base or lower portion 26 extending substantially throughout the length and breadth of the chassis and is provided with a longitudinal wall portion or rib 28 along one side thereof and an upwardly 50 facing supporting surface 30 on which is mounted a second main portion 32, preferably separate from the base, and which may be termed a flint holder, serving to slidably support the flint and feed means therefor as well as to aid in supporting the sparking wheel and other elements.

55 The flint holder 32 includes a lower block portion 34 resting on the surface 30 and engaging the wall element 28 and secured thereto by suitable means such as screws 36. Preferably a laterally extending guide pin 37 is secured in the wall element 28 for insertion into

60 an aperture 39 in the flint holder for guiding the flint holder into proper position on the base. The block portion 34 is of lesser length than the base 26 (Fig. 2) and as illustrated, may be of substantially half the length thereof. The flint holder, however, includes an upper

65 portion extending substantially the length of the base providing an overhanging arm or support 38 defining with the adjacent end of the base, a space 40 in the nature of a recess or cavity in which are mounted the sparking wheel and related operating elements of the lighter.

70 The upper portion of the flint holder 32 is provided with a longitudinal bore 42 for slidably mounting a flint 44, the bore opening at one end into the recess or cavity 40

for enabling the flint to be fed toward and into engagement with the sparking wheel 46 which is operatively mounted in the recess 40. The bore 42 may also open through the opposite end of the chassis, as shown in Fig. 2. Preferably the flint holder is provided with an opening 48 in the form of a groove communicating with the bore 42 and opening upwardly through the top of the flint holder for enabling insertion of a new flint into the bore 42 when desired, as when a previous flint is expended. The bore 42 is preferably circular in cross section to accommodate conventional flints which are commonly also circular in cross section. However, the specific cross-sectional shape of the bore and flint may be otherwise than stated, if desired.

The sparking wheel is provided with a knurled or otherwise roughened peripheral surface for engaging the flint in rotation of the wheel, and throwing sparks therefrom toward the stream of fuel issuing from the tank of the lighter as will be brought out fully hereinafter. The flint 44 is fed toward the sparking wheel by means of a flint follower 50 and spring means 52, the latter having engagement with the flint follower and being secured to the chassis at a convenient location, such as the wall element 28 of the base, as will be pointed out presently. The follower 50 is preferably in the form of a cylindrical plug-like element and may have a roughened forward surface 54 engageable with the flint, if desired, to prevent the flint from turning. The follower 50 is provided with a transverse aperture or bore 56 through which extends a shaft 58, the latter extending through side slots 60 in the flint holder (Figs. 1 and 2) and on which is mounted a negator spring 52 constituting means for urging the flint follower in direction to feed the flint toward the sparking wheel. One end of the shaft 58 is provided with an enlarged head or circular flange 62 preferably integral therewith. The other end of the shaft is provided with a similar head or flange 64 overlying the wall element 28 and spaced from the flint holder a substantial distance. The shaft and heads 62 and 64 form a drum with which the negator spring 52 cooperates, the spring encircling the shaft between the head 64 and the adjacent portion of the flint holder wall.

The negator spring 52 preferably takes the form of a plurality of leaves 66 (Fig. 10) which are preferably three in number. The leaves are stacked to form an effective single spring and at one end are together secured to the chassis at a suitable location, such as on the upper surface of the wall element 28, by means of a screw 68 inserted through apertures in the leaves and threaded into the wall element. The leaves are otherwise disconnected from each other, and are disconnected from the shaft 58, while encircling the shaft. The individual leaves are pre-stressed in coil form and each leaf may be readily coiled in a small diameter coil, but because of the plurality of leaves, the spring has substantial strength. Upon the spring being straightened it tends to re-coil. The flint follower 50 may be retracted (to the left, Figs. 1 and 2) by engagement of the thumb with the negator spring 52 or the adjacent head 64, and since the spring is connected to the chassis, the retracting movement tends to straighten the spring and upon release of the thumb from the spring or head, the tendency of the spring to re-coil urges the follower to the right (Figs. 1 and 2) and thus yieldingly feeds the flint through the bore 42 into engagement with the sparking wheel 46.

The lighter is provided with a burner tip 70 (Figs. 1, 2 and 7) from which gaseous fuel is emitted in an upwardly flowing stream or column, so located that the sparks thrown from the flint by the sparking wheel are directed into the stream. The casing 24 is provided with a suitable opening in the top above the burner tip for accommodating the stream of fuel, and the flame when the fuel is lighted, such for example as is provided in the casing of the lighter disclosed in the copending application referred to above. The fuel is fed to the burner

tip from the tank 22 through the valve means illustrated in Fig. 3 which will be described in detail hereinafter.

The tank 22 may assume any desired form but is preferably constructed generally similarly to the tank 5 of 2 of the copending application referred to above. The tank (Fig. 8) in its preferred construction includes a generally cup-shaped member 72 which, for convenience, may have a generally square overall shape although the particular shape may be as desired, as will be understood. A cover 74 is permanently and sealingly secured to the body member 72 in a suitable manner as by welding or brazing. The cover member 74 as well as the body member 72 may have suitable strengthening ribs 76 for imparting the desired strength to the tank. The tank is formed with a filling and discharge opening 78 surrounded by an inwardly turned flange or wall element 80. The opening is adapted to receive a plug 82 formed of a suitable resilient material such as a rubber-like product having sufficient resilience to provide the necessary sealing action at the opening, and which is inert to the fuel used in the lighter. "Neoprene" has been found suitable for the purpose. The plug 82 may be inserted in the opening 78 in any suitable manner and is provided with upper and lower flanges 84 and 86 for engagement with the tank portions for sealing the opening 78. The lighter is adapted for replacement of an empty tank by a full tank by the user and the full tank of fuel must, of course, be sealed until it is connected with the chassis. For this purpose the reserve tank is provided with suitable closure means, such as the plug core of the above mentioned copending application, which is fitted in the central aperture 88 of the resilient plug 82. When such tank is connected with the chassis, the plug core is removed from the central aperture 88 by the stem 90 and forced into the interior of the tank. The stem 90, forming an extension of one of the elements of the valve mechanism for controlling the flow of fuel from the tank, is of such dimensions that it is sealingly engaged by the plug 82 so as to prevent the escape of fuel therewith.

The lighter, similarly to the lighter of the above-mentioned copending application, is adapted for using fuel such, for example, as butane, which, at temperatures at which the lighter is normally to be used, takes the form of gas but which may be readily liquefied by compression and/or cooling. The fuel is introduced into the tank when the latter is charged in the form of a liquid, and preferably at a temperature below the vaporizing temperature, after which the tank is closed. When the tank is at a normal use temperature, the fuel in the tank is under substantial pressure and a portion of the fuel is in gaseous form, the remainder being in liquid form. The valve disclosed herein is adapted to conduct and control the flow of fuel from the tank and deliver it to the burner tip 70 in gaseous form. The opening 78 may be utilized for charging the tank, after which the plug and core referred to above are inserted in the plug 82.

The stem 90 not only serves as a means for directly connecting the tank 22 to the chassis 20, but also as a passage for conducting fuel from the tank to the valve mechanism of Fig. 3, from which it emerges at the lighting station. The stem 90 is of generally tubular form having a passage 92 therethrough communicating with the interior of the tank and with other passages through the chassis and valve means. The inner or lower end of the stem 90 is preferably tapered as at 94 for aiding insertion of the stem through the plug 82, the tip portion preferably having a reduced bore portion 96 communicating with the bore 92. The upper or outer end of the stem 90 includes an exteriorly threaded portion 98 and a flange portion 100. The threaded portion 98 is threaded into a bore 102 in the chassis base 26 which has an inner threaded portion and an outer, slightly enlarged portion 104. The portion 102 of the stem and the bore

102 are so dimensioned that when the body portion is threaded into the bore, the flange 100 engages the under surface of the chassis base and serves as a means for limiting insertion of the body into the bore. The flange 100 is provided with suitable sealing means such as a resilient ring-shaped gasket 106 fitted in an annular groove 108 in the flange and positioned for engagement with the under surface of the base 26 of the chassis when the portion 98 is threaded into the bore 102. The portion 98 is provided with a radial bore 110 leading from the bore 92 outwardly to the bore portion 104 and establishing communication between the two bores mentioned, whereby gaseous fuel from the tank is enabled to pass through the stem 90 and into the annular space in the bore portion 104. The gaseous fuel in the annular space passes through a bore or passage 112 formed in the body of the chassis and leading from the annular space to another and enlarged bore 114 also formed in the base 26 of the chassis. It will be noted at this point that the bore 114, which as shown in Fig. 3, contains the operating parts of the valve and the burner tip 70, is positioned in the chassis so as to properly position the burner tip 70 (Fig. 1) so that the stream of fuel issuing therefrom is properly positioned for receiving the stream of sparks from the flint when the sparking wheel is rotated clockwise (Fig. 1). The bore 114 at its lower end is interiorly threaded as at 116 for receiving a threaded adjustment screw 118 having an upwardly extending, central reduced-diameter projection 120. An annular space 122 is thus formed around the projection 120, communicating with the bore 112. The adjustment screw 118 is preferably provided with a screw driver slot 124 for engagement by a screw driver for insertion of the screw in the bore and for adjusting movement for increasing or decreasing the valve opening through the valve structure, as will be brought out in detail hereinafter. The lower end of the bore 114 is preferably closed by a suitable plug screw 126 which may be recessed into the base of the chassis and positioned substantially flush with the under surface thereof. A gasket 128 of suitable resilient sealing material is compressed between the head of the screw and the wall of the recess 127 for sealing the bore 114 and the threaded portion 116 against the escape of gaseous fluid therethrough.

The bore 114 at its upper end is provided with a relatively large counterbore 130 interiorly threaded for receiving the burner valve body 132 which contains the burner tip 70. The body 132 is of generally tubular form having a lower exteriorly threaded portion 134 threaded into the counterbore 130, a gasket 136 of suitable resilient sealing material being interposed between the valve body 132 and the bottom surface of the counterbore 130 for sealing the bore 114 at its upper end against the escape of gaseous fuel. The upper end of the valve body 132 is preferably of reduced dimension to form the burner tip 70. The bore through the valve body 132 includes three main portions, namely a lower, relatively large-diameter portion 138, a central threaded portion 140 preferably of relatively reduced diameter, and an upper portion 142 of still greater reduced diameter.

Mounted in the lower bore portion 138 is a metering plug or inlet member 144 of generally disc-like shape having a central solid portion engageable with the projection 120 and a plurality of axially extending apertures 146, preferably two in number (Figs. 5 and 6), disposed radially outwardly of the central portion and outwardly of the projection 120, forming passages communicating with the annular space 122. The apertures 146 may be of any desired number and dimension so as to provide the desired and optimum capacity for flow of gaseous fuel therethrough. Disposed above the metering plug 144 is a metering disc or outlet member 148 provided with an aperture 150 therethrough of generally cruciform shape and having laterally or radially extending wing portions 152 which, in the form utilized, are

four in number. The metering disc is positioned with opposite ones of the wing portions 152 in register and alignment with the apertures 146 in the metering plug. The width of the aperture wing portions 152 is preferably greater than the diameter of the apertures 146. The metering plug 144 and metering disc 148 are dimensioned for snug but sliding engagement with the wall of the bore 138 for sliding movement therein, in response to adjusting movement of the adjustment screw 118. Positioned above and in engagement with the metering disc 148 is a metering ring 154 of yieldable and resilient material, capable of being compressed between the metering disc 148 and the elements thereabove. The metering ring is preferably in the shape of a torus, circular in cross section when in its normal unstressed condition (Fig. 6).

The metering ring 154 is disposed between and engaged by the metering disc 148 and a valve plug 156 threaded in the central bore portion 140 of the valve body 132. The under surface of the valve plug is flush with the upper surface of the lower bore portion 138, thus presenting a continuous annular surface 158 for engagement with the metering ring 154. Upon upward adjustment of the adjustment screw 118, the metering plug 144 and metering disc 148 are moved upwardly, reducing the space between the metering disc and the surface 158 and thereby compressing the metering ring therebetween. This action results in forcing portions of the metering ring down into the aperture 150 in the metering disc, and particularly into the wing portions 152 thereof. The greater the compression force applied to the metering ring and the consequent projection of the metering ring downwardly toward the apertures 146, the greater is the restricting effect on the apertures 146 and hence reduction in rate of flow of fuel therethrough. Upon adjusting of the adjustment screw 118 in the opposite direction, i. e. downwardly, the space between the metering disc and surface 158 is increased, enabling the metering ring to tend to resume its toroidal shape which, as a consequence, retracts a proportional extent from the aperture wing portions 152, and from the apertures 146, enlarging the effective opening from the latter apertures and permitting a greater rate of flow of fuel. Similar contraction and expansion of the metering ring takes place in response to changes in temperature ambient to the lighter. For this purpose the metering ring 154 is made of a suitable elastomer having a relatively high coefficient of thermal expansion, whereby in response to increased ambient temperature it expands and projects farther into the aperture wing portions 152 and tends to close the apertures 146 and thus reduce the effective opening thereof, compensating for the tendency to greater rate of flow due to increased pressure of the gas caused by increased ambient temperature. Upon lowering of the ambient temperature, the metering ring contracts, and withdraws or retracts a proportional amount from the apertures 146, in a manner described above in connection with adjustment of the adjustment screw 118. Thus regardless of the ambient temperature, the rate of flow of fuel through the valve remains substantially constant and hence the height of the flame produced thereby remains substantially constant.

The valve plug 156 is provided with a bore 160, and has an enlarged recess 162 in its under surface, which may be polygonal in shape for engagement by a suitable tool for inserting the valve plug into the bore 140. The bore 160 extends upwardly through the valve plug which has a reduced tapered portion 164 extending upwardly into the bore 142 of the valve body. The bore 160 in the valve plug is adapted to be closed by a valve closure or shut-off member 166 which preferably includes a resilient valve seat 168 formed of sealing material and suitably mounted as in a valve seat housing 170, slidably mounted in the bore portion 142. The housing 170, as illustrated, is preferably cup-shaped for receiving the valve seat 168 which is secured therein in any suitable

manner, and has an outer substantially cylindrical surface for guiding and sliding engagement with the surface of the bore portion 142. Upon depression of the valve closure member 166 the valve seat 168 engages the upper end of the valve plug 156 and closes the bore 160 against the flow of fuel therethrough. A suitable ball 172, which is preferably rigid and may be made of steel, is disposed in the bore portion 142 above the valve member 166. The ball is freely rotatable and reciprocable in the bore and is held therein by inturned or peened portions 174 formed on the upper edge of the inner surface of the bore portion 142. The dimensions of the various elements are such that when the ball 172 is uppermost and engaged with the peened portions 174, its upper portion extends out of the bore for engagement by a lever arm 176 which will be referred to again in connection with the means for actuating the sparking wheel. The inner surface of the bore portion 142 is provided with a plurality of grooves 178, preferably four in number (Fig. 4) opening through the top of the burner tip 70 and extending downwardly to a position at least below the upper end of the valve plug 156 for providing passages for flow of fuel therethrough and past the ball. The ball 172 thus serves only as a valve-closing member and does not close the burner tip outlet. Gaseous fuel, upon issuing upwardly through the bore 160 in the valve plug, lifts the valve member 166, except when the valve member is held down, passes into the bore portion 142 below the valve member, and flows through the grooves 178 in by-passing relation to the valve member 166 and ball member 172. The valve closure member 166 and ball 172 are dimensioned for easy sliding movement in the bore portion 142 so that they may be lifted by the pressure of the gaseous fuel in and issuing from the bore 160 when the restraining force is removed from the ball. When the ball is depressed by the lever arm 176 the required yieldability for closing the bore 160 is provided by the resilient valve seat 168. The lever arm 176 includes an aperture or hole 180 (Fig. 3) of sufficiently great dimensions to enable the ball to move upwardly, until limited by the peened portions 174, to thereby provide the desired opening for issuance of the fuel from the burner tip 70. The conditions under which the hole or aperture 180 is disposed in register with the ball 172 will be described in connection with the mechanism for operating the sparking wheel 46, the lever arm 176 in which the hole 180 is formed being directly manipulated by the user in the act of operating the lighter.

The sparking wheel 46 (Fig. 2) is rotatably mounted on a shaft 182 extending vertically through the recess or cavity 40, the shaft supporting not only the sparking wheel but certain other related operating elements as well. The shaft 182 is suitably mounted in the chassis as by means of a recess 184 in the base 26 which receives the lower end of the shaft and the overhanging arm portion 38 on the flint carrier 32. The upper end 186 of the shaft is preferably of reduced diameter and fitted in an aperture 188 in the overhanging arm portion 38, the reduced portion 186 forming a shoulder engaged by the under surface of the overhanging arm portion for properly securing the shaft in position against axial displacement, and the overhanging arm portion similarly retains the elements mounted on the shaft against displacement axially of the shaft. It will be understood that the shaft 182 together with the elements mounted thereon may be inserted in position upon removal of the flint carrier 32 from the base 26, after which the flint carrier portion is inserted in position and secured to the base.

The sparking wheel 46, or flint wheel as it is sometimes called, is arranged for rapid rotation through a predetermined angular movement in response to the tensioning of a spring which is tensioned by an element actuated by the thumb or finger of the user. It is desired that the sparking wheel be rapidly rotated so that a greater spark will be produced than would be the case if

the sparking wheel were rotated slowly as often is the case when it is rotated directly by the thumb of the user in operating the lighter. Thus, the spring is tensioned by an element moved by the thumb, during which time the sparking wheel is restrained against rotation, and when the spring is properly tensioned the sparking wheel is released and the tension in the spring causes the sparking wheel to be rapidly rotated.

The lever arm 176, which is actuated by the user for rotating the sparking wheel and controlling the valve means (Fig. 3), is mounted for rotation on the axis of the shaft 182 and includes an operating handle 190 (Fig. 1) projecting through a suitable opening in the casing 24 to the exterior and positioned for convenient engagement by the thumb. The lever arm also includes a plate-like portion or sector 192 overlying the burner tip 70, in close proximity thereto, in which the hole 180 therein is formed, and positioned for registering with the burner tip in a predetermined position of the lever arm. The plate-like portion or sector 192 is generally in the form of a quadrant for controlling the valve means (Fig. 3) throughout rotation of the lever arm substantially 90°, as is desired, in the act of operating the lighter. The lever arm 176 is directly mounted on and supported by a housing 194 mounted on the shaft 182, which may also be referred to as the driver spring housing, containing a driver spring 196. The housing 194 includes a generally cup-shaped upper housing proper 197 and a lower tubular hub portion 199 snugly engaging the shaft, but preferably rotatable thereon. The housing has bearing support on the base 26 as in a recess 201, and is provided with an annular recess 198 in its outer surface adjacent its upper edge, forming a reduced-diameter extension 200 extending into an opening 202 in the lever arm 176 and serving as a means for mounting the lever arm. The lever arm is secured to the housing 194 by suitable means such as by soldering or brazing at 204, for effecting rotation of the housing 194 in response to the rotation of the lever arm. The recess 198 is suitably dimensioned so that the upper surface of the lever arm is substantially flush with the upper surface of the reduced portion 200 for forming a continuous annular bearing surface for supporting a driver 206. The driver 206 is generally in the form of a ring but with certain conformations formed in its periphery, as will be described in detail hereinafter (Figs. 11, 13). The driver is provided with a tubular hub 208 rotatably mounted on the shaft 182, and preferably formed as a separate piece from the driver 206 and secured thereto in a suitable manner such as by soldering or brazing at 210, the hub having a reduced central portion extending into the central aperture of the driver 206 forming a convenient means for mounting the driver and hub together.

The driver spring 196 contained in the housing 194, in surrounding relation to the shaft 182 and hub 208, is arranged for rapidly rotating the sparking wheel in the manner referred to above and to this end is connected effectively to the driver 206 and lever arm 176. One end portion of the driver spring 196, e. g. the lower end portion, is turned outwardly at 212 and fitted in a radial aperture 214 formed in the wall of the housing 194 while the other and upper end portion 216 is turned inwardly and fitted in a recess 218 in the hub 208. Thus, when the housing 194 is rotated by rotation of the lever arm 176, the rotational force is transmitted through the driver spring 196 and when the driver 206 is held against rotation, as it is throughout a portion of the lighting operation, in a manner to be explained hereinafter, the spring 196 is tensioned. Then later, when the driver 206 is released, toward the end of the rotational movement, the tension in the spring rapidly rotates the driver which, through a driving connection, rotates the sparking wheel 46.

The driving connection between the driver 206 and the sparking wheel includes a clutch 220 connected with the

driver 206 for rotation therewith. The clutch is preferably formed as an element separate from the driver for the sake of convenience in manufacturing, and when connected thereto is effectively unitary therewith. The clutch includes a clutching element releasably engageable with the sparking wheel for advancing the sparking wheel in one direction and enabling the clutch to move in retracting direction while the sparking wheel is held against rotation (as explained below), for enabling the clutch to be positioned successively for advancing the clutch in each actuation of the lever arm 176. The clutch 220 is preferably in the form of a relatively thin annular disc or wafer having a central aperture 222 (Fig. 11) fitted on the shaft 182 and dimensioned for enabling rotation relative thereto and about the axis thereof. The clutch 220 is provided with a lug 224 (Figs. 11 and 12) at a convenient location on its periphery turned down and fitted into a complementally shaped recess or notch 226 formed in the periphery of the driver 206. The driver and clutch are both restrained against lateral play and substantial axial play and thus the lug 224 is retained in the notch. The lug 224 has adequate axial dimension so as to be restrained against axial displacement in the incidental but small axial play permitted by the clutch. Such axial play results from the space between the driver and the sparking wheel as is necessary for proper actuation of the clutch through the clutching finger 228 on the clutch (Figs. 2 and 11) which forms the means for engaging the sparking wheel and rotating it in response to rotation of the clutch. The clutching finger 228 is preferably formed by means of cutting or slotting the clutch as at 229 (Fig. 11), and bending the portion thus formed upwardly so that its extended end projects at an angle to the plane of the clutch (Figs. 2 and 7). The material from which the clutch is formed is preferably spring metal so that the clutching finger 228 will return to its normal shape and position after being flexed therefrom. The clutching finger is normally biased upwardly into the desired position but enabled to flex downwardly toward the plane of the clutch. The clutching finger 228 is positioned for engaging the teeth 230 formed in the lower surface of the sparking wheel 46 (Figs. 2 and 7). Upon rotation of the clutch 220 in the intended direction (clockwise, Figs. 1 and 11), the clutching finger 228 engages one of the teeth 230 and rotates the sparking wheel in that direction. In the reverse and retracting direction, the sparking wheel is normally retained against rotation by reason of the friction between the sparking wheel and flint, and the clutching finger 228 rides on the camming surfaces 232 of the teeth, being deflected downwardly or toward the plane of the clutch, enabling it to ride past one or more teeth so as to position it for engaging with a successive tooth in the next operation. The sparking wheel may be provided with any desired number of teeth 230 but preferably five such teeth are provided, whereby since it is desired that the driver 206 be rotated substantially a quarter turn in each operation, latitude is provided for assuring that the clutching finger is retracted after each operation sufficiently for engaging the successive tooth on the sparking wheel.

Means is provided for restraining the sparking wheel against rotation throughout the greater portion of the rotation of the lever arm 176 and releasing the sparking wheel toward the end of the movement of the lever arm for accomplishing the result noted above, namely, rapid rotation of the sparking wheel. Such restraining means includes a holding pawl 234 suitably mounted on the base 26 of the chassis and positioned for engagement with the driver 206. The pawl 234 is pivotally mounted at one end on the chassis as on a boss or projection 236 by suitable means such as a screw 238. The boss or projection 236 is of proper height for positioning the holding pawl substantially in the plane of the driver 206 (Fig. 2). The holding pawl is disposed in the cavity or recess 40 with its free end swingable toward and from

the driver 206, being biased toward the driver by suitable means, such as a spring 240 which, in the present instance, may conveniently take the form of a V-shaped spring having one leg secured to the chassis, as by a screw 242, and its other leg in engagement with the pawl, the normal biasing effect of the spring urging the free end of the pawl toward the driver. The holding pawl 234 is provided with a notch 244 cooperable with a lug 246 formed in the periphery of the driver 206. The notch and projection are complementally formed with abutting surfaces shaped to prevent rotation of the driver in clockwise direction (Fig. 11) when they are in interengagement, for example, extending generally radially of the driver, but with respective camming surfaces on the opposite sides for enabling the projection to ride out of the notch when the driver is rotated in the opposite or retracting direction. The driver 206 is also provided with a peripheral notch or cut-out portion 248 leading in a counterclockwise direction from the projection 246 (Figs. 11-13) and having an end surface 249, for receiving a pin 250 on the lever arm 176. The pin 250 serves both as a means for releasing the holding pawl 234 and as a stop for limiting the extent of rotational movement of the driver 206 in advancing direction, as well as for returning the driver to its initial position by the lever arm, as will be described more fully hereinafter.

The lever arm 176 and driver 206 are together returned or retracted to a normal position by means of a return spring 252 having connection between the base of the chassis and the housing 194. It will be recalled that the lever arm 176 is connected with the housing 194 and rotary movement imparted to one of the elements is transmitted to the other, and return of the housing to its initial position effects return of the lever arm. The return spring 252 is positioned in surrounding relation to the hub 199 and has one end 256 appropriately shaped and fitted into a recess 258 formed in the chassis while the other end 260 is suitably shaped and fitted in a recess 262 in the hub 199. Rotation of the housing 194 in one direction relative to the base tensions the return spring 252 and upon release of the rotational force, the return spring returns the housing to its initial position. The means for limiting the extent of rotational movement of the housing 194 may take any of several desired forms but preferably it includes a stop pin 266 mounted in the base of the chassis and positioned in a cut-out portion or notch 268 (Figs. 2 and 15) in the lower end of the hub 199. The notch 268 is of the desired circumferential dimension for enabling rotational movement of the lever arm 176, as desired, which, in the present instance, is preferably on the order of 90 degrees. The opposite surfaces of the notch 268 alternately engage the stop pin and limit the rotational movement of the driver housing 194 and lever arm 176 in both directions.

The initial position of the lever arm 176 is as shown in Figs. 1 and 11 where it is normally retained by the return spring 252. The plate element 192 in all positions overlies the ball 172 of the burner tip 70, but in its initial position and all but more advanced positions (Figs. 12 and 13) an imperforate portion thereof engages the ball to retain the valve controlled thereby closed. The valve is permitted to open only when the plate element approaches the fully advanced position wherein the hole 180 registers with the ball. In the initial position of the lever arm, the driver 206 is disposed in its initial position, which is that shown in Fig. 11, being so positioned by virtue of the pin 250 on the lever arm, which engages the end surface 249 of the peripheral notch 248 in the driver and moves the driver to its initial position upon movement of the lever arm in retracting direction (counterclockwise). Further, in the initial position of the parts, the holding pawl 234 is as shown in Fig. 11 wherein the notch 244 and projection 246 are in holding or latching relation.

To operate the lighter, the user places his thumb on the operating handle 190 and rotates the lever arm 176 clock-

wise (Figs. 11-13). The driver 206 is restrained against such movement, which would otherwise result through the driver spring 196, by the holding pawl 234. Toward the end of the rotational movement of the lever arm, the pin 250 riding in the notch 248 engages the holding pawl and swings its free end away from the driver against the action of the spring 240, disengaging the notch 244 and the projection 246. During this movement of the lever arm 176, the driver spring 196 is tensioned since the driver 206 is restrained against rotation, but when the holding pawl 234 is released, as just described, the tension in the driver spring 196 operates to rotate the driver 206. The driver is, therefore, rapidly rotated and its rotation is transmitted through the clutch 220 which, as above referred to, is effectively unitary with the driver, and the clutch in turn, through engagement of the clutching finger 228 with one of the teeth 230 of the sparking wheel, rotates the sparking wheel. The rotational movement of the lever arm 176 in clockwise direction in the use of the lighter is limited by the stop pin 266 (Fig. 15) and the rotational movement of the driver 206 is limited by engagement of the end surface 249 with the pin 250 on the lever arm.

During the fore portion and major portion of the movement of the lever arm 176 in advancing direction, an imperforate portion of the plate element 192 remains in engagement with the ball 172 in the burner tip 70 and retains the valve (Fig. 3) closed so that no gaseous fuel emerges from the burner tip. However, the valve is permitted to open at an instant before the sparking wheel is rotated so that the desired stream or column of gas reaches up into the path of the sparks at the time the sparks are produced. This is accomplished by the provision of the hole 180 referred to above and formed in the lever arm 176. The hole is appropriately dimensioned in circumferential direction, and positioned adjacent the far or trailing edge of the plate element 192, relative to advancing movement of the latter, so that it is in register with the ball for permitting the ball to rise and the valve to open shortly before the holding pawl 234 is released, and to remain open in fully advanced position. The gaseous fuel in the valve which stands at the upper end of the bore 160 then flows, when the valve is open, upwardly through the bore 142 and through the hole 180 and forms a stream or column above the burner tip of sufficient height to be ignited by the sparks issuing from the flint.

So long as the user holds the lever arm 176 in advanced position wherein the hole 180 registers with the ball in the valve, a flame continues and so continues until the user releases the handle member 190 and permits the lever arm 176 to be retracted. Upon retracting movement of the lever arm of only a small amount, the hole 180 moves out of register with the ball and the imperforate portion of the plate element 192 reengages and depresses the ball and closes the valve. It will be recalled that in advanced position, the shoulder 249 on the driver 206 is in engagement with the pin 250 and upon retracting movement of the lever arm 176, the pin 250 acting through the shoulder 249 retracts the driver 206 with the lever arm. The lever arm and driver during such retraction movement thus act as a solid and unitary member whereby the driver spring 196 has no effective reaction between the connected parts and therefore produces no countereffect to the return spring 252. The clutch 220 being connected with the driver 206 is also returned with the latter, and in the returning or retracting movement the clutching finger 228 rides under the camming surfaces 232 of the teeth 230. A suitable space is provided between the clutch 220 and the sparking wheel 46 so as to enable the clutching finger 228 to be flexed or depressed a suitable extent without being depressed entirely into the plane of the body of the clutch. Preferably the sparking wheel 46, as well as all the other elements mounted on the shaft 182, are rotatable relative to the shaft so that the shaft may remain stationary.

The various elements are maintained in position axially of the shaft by reason of the appropriate dimensioning of the elements relative to the recess or cavity 40, the clutching finger 228 through its resilient character aiding in maintaining the various elements in proper axial position. It will be understood that as a practical matter and in view of the small dimensions of the various elements, the clutching finger 228 will effectively maintain the elements in the desired axial positions.

10 The driver housing 194 is of appropriate axial dimension, as will be understood, for positioning lever arm 176, and particularly the plate portion 192 thereof, immediately above the burner tip 70 in position for engaging the ball 172.

15 The invention also encompasses a modified form of valve for controlling the flow of gaseous fuel from the tank to the lighting station. Such a valve is shown in Fig. 16 and may be employed instead of the valve illustrated in Fig. 3. In the valve of Fig. 16, the base 26 of the chassis 20 is provided with a bore 270, similar to the bore 112, leading from the annular space 104. The bore 270 leads to a bore 272 formed in the base of the chassis and in which the valve means is positioned. The bore 272 communicates downwardly with a threaded bore 274 which terminates in a counterbore 276. A screw plug 278 is threaded in the bore 274 and provided with a resilient gasket 280 engaged by the head of the screw plug and forming a sealing means against the escape of gaseous fuel from the bore in that direction. Preferably, the screw plug is provided with a screw driver slot 282 for reception of a screw driver for inserting the screw, and adjusting it thereafter in the bore.

20 Positioned in the bore 272 is a resilient metering plug 284 preferably formed of a suitable elastomer or rubber-like product such as "Neoprene." The metering plug may be substantially solid and is adapted to be compressed for restricting the flow of gaseous fuel through the valve in response to adjustment of the screw plug 278, as will be explained more fully hereinafter. The metering plug, similarly to the metering ring 154 of Fig. 3, is made of a material having a relatively high coefficient of expansion and thus expandable and contractable in response to changes in ambient temperature, for controlling the flow of fuel through the valve, in a manner to be referred to hereinbelow. The metering plug 284 is appropriately dimensioned for forming an annular space 286 between itself and the surface of the bore 272.

25 The bore 272 communicates upwardly with a threaded counterbore 288 in which is disposed a valve plug 290 provided with a flange 292 at its lower end and cross grooves 294 in its lower end surface. The grooves 294 may conveniently consist of a pair of transverse grooves extending across the end surface of the valve plug leaving wedge-shaped portions of substantial dimensions between the grooves for engagement by the metering plug 284. The valve plug 290 is normally maintained rigidly in position, as will be explained presently, and serves as a reaction element against which the metering plug engages for expansion and contraction of the metering plug in response to adjustment movements of the screw plug 278. In response to inward adjusting movement of the screw plug, the metering plug 284 is compressed between the screw plug and valve plug and distorted and forced into the grooves 294, as indicated at 295 in Fig. 17, and when the screw plug is adjusted outwardly, the metering plug is enabled to retract from such position. Thus the effective opening of the grooves 294 can be varied for controlling the rate of flow of the gaseous fuel therethrough and thereby through the valve.

30 The valve plug 290 is provided with a central longitudinal bore 296 and a central tapered projection 298 on its upper end through which the bore 296 opens. The upper face 300 of the projection 298 is preferably hol-

lowed or slightly concave, presenting an annular edge 302.

The valve plug 290 is maintained rigidly in position by a tubular member 304 having a lower threaded portion 306 threaded into the threaded bore 288. A resilient gasket 308 is interposed between the lower end of the tubular member 304 and the flange 292 on the valve plug. In response to threading down the tubular member 304, the gasket 308 is compressed into engagement with the surface of the bore 288 and the surface of the valve plug to prevent the escape of gaseous fuel therewith. The upper end 310 of the tubular member 304 forms a burner tip similar to the burner tip 70 of Fig. 3.

For the purpose of closing the valve, a valve closer or shut-off member 312 is provided, which preferably includes a head 314 and a stem 316. The head 314 is dimensioned relative to the inner surface of the burner tip 310 to form a space therewith for the free flow of gaseous fuel therethrough, and the stem is dimensioned for free sliding movement in the bore 296. The valve closer 312 is provided with a resilient valve seat 318 having a central aperture for receiving the stem 316, and seated against the under surface of the head 314. The stem 316 serves as a guide for the valve closer member 312 in its vertical movements, but is so dimensioned as to provide a space between itself and the bore 296 to permit the free flow of gaseous fuel through the bore when the valve closer is removed from the seat 302. The valve closer 312 is depressed by means of a ball 320 of rigid material, and preferably made of steel, disposed above the valve closer and held in the burner tip 310 by means of a disc or plug 322 having a central aperture 324 into and through which the ball projects. The surrounding surface of the aperture 324 has its upper edge peened over as at 326 so as to retain the ball in the burner tip. The disc or plug 322 is preferably provided with a plurality of axially extending apertures 328, which are preferably eight in number, arranged around its periphery and spaced radially outwardly from the central aperture 324. The disc or plug 322 may be retained in the burner tip in any suitable manner such as by a press fit. Preferably the central aperture 324 is so dimensioned relatively to the ball that the gaseous fuel is enabled to pass around the ball and through the aperture, and to the same end the surface of the central aperture 324 may be provided with grooves similar to the grooves 178 of Figs. 3 and 4. The valve ball 320 is actuated by the lever arm 176 in a manner similar to that described in connection with Fig. 3; i. e., when the imperforate portion of the lever arm overlies the burner tip, it engages the ball and depresses it, forcing the valve closer 312 into shut-off position wherein the valve seat 318 sealingly engages the valve seat 302. When the hole 180 registers with the ball, the latter is enabled to move upward for enabling the valve closer 312 to open. The lever arm 176 may also be provided with a plurality of holes 330 which register with the perimeter apertures 328 when the hole 180 registers with the ball, to facilitate the flow of the gaseous fuel from the apertures 328 upward into the stream or column reaching to the path of the sparks from the sparking wheel. The pressure of the gaseous fuel, similarly to the condition described in connection with Fig. 3, is sufficient to lift the valve closer 312 from the valve seat 302 when the hole 180 registers with the ball, enabling the fuel to flow through the valve and out of the burner tip.

In both valve structures, namely, that of Fig. 3 and that of Fig. 16, the valve can be adjusted manually for predetermining the rate of flow of gas and hence the height of the flame produced when the lighter is lighted. In the present construction (Fig. 16) that result is produced by adjusting the screw plug 278 which, when adjusted inwardly, compresses the metering plug 284 and forces it into the grooves 294. Also in both constructions the rate of flow of gas, and consequent height of

the flame when the lighter is lighted, is automatically adjusted to compensate for changes in ambient temperatures. This feature was described above in connection with Fig. 3, and in the construction of Fig. 16 is automatically adjusted through the expansion and contraction of the metering plug 284 in response to changes in the ambient temperature. For example, when the ambient temperature rises, the metering plug 284 expands and restricts the grooves 294. The pressure of the gas also rises and tends to flow faster because of the increased pressure; but, because of the relatively restricted passages when the temperature rises, the rate of flow of the gas therethrough remains substantially constant so that the height of the flame produced is substantially constant regardless of changes in the ambient temperature.

I claim:

1. A lighter comprising a chassis, a fuel tank connected to said chassis, a fuel outlet passage leading from said tank, means for controlling the flow of fuel from said outlet passage including a normally open valve and a freely rotatable ball reciprocable relatively to said valve for closing the latter, a sparking wheel rotatably carried by said chassis, a flint, means urging said flint into engagement with said sparking wheel, a drive element pivotally carried by said chassis for movement between two limit positions and having a portion movable over and into rolling contact with said ball when said drive element is moved into one said limit position for depressing said ball to close said valve, a one-way drive connection between said drive element and said sparking wheel for rotating the latter when said drive element is moved from its said one limit position to the other, and spring means resiliently urging said drive element toward its said one position.

2. A lighter comprising a chassis, a fuel tank connected to said chassis; a fuel outlet passage leading from said tank and terminating in a burner tip, means for controlling the flow of fuel from said outlet passage including a normally open valve, and a valve-closing ball freely rotatable and reciprocable in said burner tip for closing said valve, a sparking wheel rotatably carried by said chassis, a flint, means urging said flint into engagement with said sparking wheel, a drive element pivotally carried by said chassis for movement between two limit positions and having a portion movable in a plane closely adjacent the end of said burner tip and engageable with said ball when said drive element is in one said limit position for closing said valve, a one-way drive connection between said drive element and said sparking wheel for rotating the latter when said drive element is moved from its said one limit position to the other, and spring means resiliently urging said drive element toward its said one position.

3. A gaseous fuel lighter comprising a fuel tank, an outlet passage leading from said tank, a burner tip having a generally circular discharge opening connected to said passage and formed with a plurality of circumferentially spaced notches in its perimeter, a control valve in said passage, and means for actuating said valve including a ball freely rotatable and reciprocable in said burner tip and projecting beyond the end thereof and substantially closing said discharge opening except at said notches.

4. A gaseous fuel lighter comprising a fuel tank, an outlet passage leading from said tank, a burner tip having a generally circular discharge opening connected to said passage and formed with a plurality of circumferentially spaced notches in its perimeter, a control valve in said passage, including an orifice element having a restricted orifice therein and sealing member positioned to overlie said orifice, and means for urging said sealing member into position closing said orifice including a ball freely rotatable and reciprocable in said burner tip and projecting beyond the end thereof and substantially closing said discharge opening except at said notches.

5. A lighter comprising a chassis, a fuel tank connected

to said chassis, said chassis having a fuel outlet passage therethrough leading from said tank and terminating in a burner tip, means for controlling the flow of fuel through said outlet passage including a normally open valve and a valve-closing ball freely rotatable and reciprocable in said burner tip and projecting through the burner tip, means for producing sparks and projecting them to a position adjacent said burner tip including a flint and a rotatable sparking wheel, a lever mounted on said chassis for pivotal movement between a first position and a second position, said lever having an imperforate portion engaging said ball and thereby retaining said valve closed in all positions of the lever except said second position and having an opening registering with said ball in said second position and enabling the ball to project thereinto and enabling the valve to open, means controlled by movement of said lever for rotating said sparking wheel only when said lever is substantially in said second position, and yieldable means urging said lever to said first position.

6. A lighter comprising a chassis, a fuel tank connected to said chassis, an outlet passage leading from said tank and terminating in a burner tip, valve means for controlling flow of fuel through said passage, means for producing sparks and projecting them to a position adjacent said burner tip including a flint and a rotatable sparking wheel, a lever arm, a shaft, a housing supporting said lever arm and rotatably mounted on said shaft for pivotal movement of said lever arm in retracting direction to a first position and in advancing direction to a second position, one-way rotatable clutch means engageable with said sparking wheel, tension spring means in said housing interconnected between said housing and said clutch means, means controlled by said lever arm for closing said valve means in all positions of said lever arm except said second position and enabling opening of the valve means in said second position, means controlled by said lever arm for restraining said clutch means against rotation except in said second position, return tension spring means interconnected between said housing and chassis urging said housing in retracting direction, and stop means on said chassis engageable with said housing for limiting rotational movement of the housing in both directions.

7. Valve means comprising a body having a passage therethrough, shut-off valve means in said passage, manually actuatable means for controlling said shut-off valve

10

means, and adjustable flow restricting means in said passage including an inlet member having a plurality of circumferentially spaced inlet passages extending therethrough, an outlet member having a generally cruciform outlet passage including radially extending outer portions extending therethrough and overlying said inlet passages, a resilient ring disposed against said outlet member and overlying and closing the radially outer portions of said outlet passage, and means for adjustably compressing said ring and thereby spreading it radially inwardly to adjust the extent it restricts said outlet passage.

8. In a gaseous lighter, a fuel tank, means forming an outlet passage leading from the fuel tank, manually actuatable shut-off valve means in the outlet passage, a metering plug in the passage having ports adjacent its periphery, a metering disc adjacent the metering plug and having radially arranged passages communicating with said ports, and a resilient metering ring fitted to the metering disc and defining the path of the passage from the ports to the central space of the ring, and means accessible to the exterior for adjustably compressing the metering ring for restricting the flow of gas through the passage.

9. The combination of claim 8 wherein the metering ring upon compression thereof is projected axially into the radial passages toward said ports.

10. The combination of claim 8 wherein the resilient sealing ring is retained on one side by an insert in the passage having a central bore defining an outlet port against which the shut-off valve means bears to close the outlet passage.

11. The combination of claim 8 wherein the exteriorly accessible adjusting means includes a screw threaded in the passage and having a reduced inner extremity bearing against the central portion of the metering plug.
